UNITED STATES PATENT OFFICE.

JACOB SCHOONHOVEN, OF SHANNON, ILLINOIS.

SHOCKER-MACHINE.

1,232,854.

Specification of Letters Patent. Patented July 10, 1917.

Application filed March 1, 1916. Serial No. 81,524.

To all whom it may concern:

Be it known that I, JACOB SCHOONHOVEN, a citizen of the United States, residing at Shannon, in the county of Carroll, State of Illinois, have invented certain new and useful Improvements in Shocker-Machines; and I do hereby declare the following to be a full, clear, and exact description of the invention, such as will enable others skilled 5 in the art to which it appertains to make and use the same.

This invention relates to farm machinery and more particularly to machines for shocking grain, and has for its object to provide a machine which may be attached to a binder and which will include means for forming the grain bundles into shocks as they come from the binder, and for placing the shocks so formed in upright position 10 upon the ground.

Another object is to provide a machine so arranged that its motion over the ground will be neutralized at the time that a shock is being deposited on the ground so as to 15 prevent the shock from being pulled over before it is released from the mechanism.

Another object is to provide a machine so constructed that it will be practically automatic in its operation.

Another object is to provide a machine including means for interrupting the discharge of bundles from the binder during the time that one shock is being deposited upon the ground.

Other objects and advantages will be apparent from the following description:

In the drawings:

Figure 1 is a front elevation of the structure with the shock former in receiving position, the closed position of the shock former being indicated in dotted lines, the machine being shown attached to a binder which is conventionally illustrated and of which parts unnecessary to the present invention 40 are omitted.

Fig. 2 is a rear elevation of the present invention with the shock former in discharging position.

Fig. 3 is a top plan of the mechanism 50 connected from the binder with the shock former in receiving position.

Fig. 4 is a side elevation of the mechanism with the shock former in discharging position, a part of the frame being broken away.

Fig. 5 is a longitudinal section taken centrally through the machine.

Fig. 6 is a detail horizontal section taken

through the forward end of the machine in the plane of the trip cable, the releasing finger of the shock former being shown in engagement therewith, the parts being shown as though looking upwardly.

Fig. 7 is a detail elevation of the discharge interrupting mechanism partly in section.

Fig. 8 is a detail section through the support for the guide rod.

Fig. 9 is a section taken through the mounting of the shock former upon the rails.

Fig. 10 is a detail perspective of part of the shock former showing a latch and adjacent parts.

Fig. 11 is a fragmentary top plan, showing the shock former in discharging position.

Referring now to the drawings the present invention comprises a horizontally disposed frame 15 including parallel side members 16 and 17 and a connecting front end 80 member 18.

The side member 17 is provided with hooks 19 extending outwardly therefrom and adapted to be engaged with the frame work of a binder A to hold the present 85 mechanism to the binder. Additional fastening devices may be used if desired. The rearward end of the side member 17 carries a caster wheel 20 which acts as a support for the rearward end of the machine. A transverse shaft 21 is mounted upon the underfaces of the side members adjacent to the forward end thereof and extends outwardly beyond the member 16, this shaft carrying a bull wheel 22 upon its outer end, the wheel 90 being provided with a sprocket 22' mounted for rotation therewith.

Two guide rails 23 and 24 are provided, these rails being secured at their forward ends to the connecting member 18 of the 100 frame, with the rail 23 adjacent to the member 16 of the frame and with the rail 24 adjacent to the member 17 of the frame. The two rails extend rearwardly approximately in parallel relation for a short distance, as indicated at 25 and beyond this portion 25 the rail 23 is curved upwardly and rearwardly and then curved laterally and rearwardly as indicated at 26 to extend approximately across the frame, when it is 110 curved longitudinally and rearwardly as indicated at 27 to a point adjacent to the rearward end of the frame where it is directed downwardly and rearwardly as indicated at

28 and has its rearward end mounted upon the inner face of the member 17 in a bracket 30 which holds the rearward portion of the rail spaced from the member 17.

5 The rail 24, rearwardly of its portion 25 is curved downwardly and rearwardly and then laterally as indicated at 31, and is then curved upwardly and rearwardly as indicated at 32 to a point horizontally opposite 10 the portion 27 of the rail 23, when it is turned downwardly and rearwardly as indicated at 33 in parallel relation to the portion 27 of the rail 23 and at the opposite side of the frame therefrom. The rearward 15 portion of the rail 23 is turned more directly downwardly as indicated at 34 in parallel relation to the portion 28 of the rail 23, the rearward extremity of the rail 24 being mounted upon a bracket 35 projecting 20 from the inner face of the member 16 to hold the rearward portion of the rail 24 in spaced relation to the inner face of the member. It will thus be seen that each rail has its ends mounted at opposite sides 25 of the frame, the rails having a general longitudinal trend, and that the rails are crossed at points between their ends, the crossing portions having compound curves therein so that one rail is curved down- 30 wardly while the other rail is curved upwardly, the rearward portions of the two rails being inclined downwardly in parallel relation and having more abrupt downward bends at points adjacent to their rearward 35 extremities. In this way there is formed what may be termed a helical track extending longitudinally of the frame.

A bar 36 is mounted to extend between the rails 23 and 24, this bar having reduced 40 extremities 37 forming pintles to receive plates 38 which are provided with outwardly extending parallel stub shafts 39 at their ends, these stub shafts having mounted thereon peripherally grooved rollers 40. These rollers are thus mounted in pairs at each end of the bar 36 and each pair of rollers receives one of the rails 23 and 24 therebetween. By this structure the bar may be moved from end to end of the 45 track which is formed by these rails, the rollers acting to support the bar upon the rails, and the pivotal connection of the bar with the plates 38 permitting rotation of the bar upon its longitudinal axis.

55 The bar 36 serves to support a shock former 41 which is mounted thereupon between the ends thereof. This shock former consists of a central, longitudinal member 42, which is secured at one end upon the bar 60 by means of bolts 43 and 44 passed therethrough and through the bar, blocks 45 being engaged with these bolts between the member 42 and the bar to form a guide passage 46 between the member 42 and the bar for a purpose to be presently described.

The shock former also consists of two transversely curved side members 47 extending longitudinally of the member 42 and hinged to the sides thereof with their concave surfaces directed inwardly, these 70 side members 47 being tapered toward one end and being disposed with their major ends adjacent to the bar 36. The member 42 is also tapered transversely away from the bar. It will thus be seen that the shock 75 former includes two side portions which are movable toward and away from each other, and that this shock former is mounted at one end upon the bar 36 and extends longitudinally beyond the bar, and that the 80 shock former is shiftable longitudinally of the machine through the movement of the bar upon the track formed by the rails 23 and 24.

Means is provided for supporting and 85 guiding the end of the shock former which projects from the bar. This means includes a rod 48 secured to the outer end of the member 42 and extending longitudinally therebeyond. An upright stanchion 49 is 90 secured to the member 16 of the frame adjacent to its rearward end and has a transverse opening 50 in its upper end. A lateral bracket 51 is carried by the upper portion of the stanchion and extends inwardly of 95 the frame 15 above the space between the rearward portions of the rails 23 and 24, this bracket having an eye 52 at its inner end which registers with the opening 50 to receive a horizontal rod 53 having threads 100 54 formed thereon to extend at opposite sides of the upper end of the stanchion. Nuts 55 are engaged with the rod at opposite sides of the stanchion and by means of these nuts the rod may be adjusted laterally 105 to shift its inner end transversely of the frame 15.

Upon the inner end of the rod 53 there is pivotally mounted a transverse plate 56 and this plate carries a pair of peripherally 110 grooved rollers 57 which receive the rod 48 therebetween. These rollers thus form a mounting for the rod 48 which permits of longitudinal movement of the rod with respect thereto, and which also permits of 115 rotary movement of the rod upon its longitudinal axis. The pivotal connection of the plate 56 with the rod 53 provides for swinging movement of the rod 48. The adjustment of the rod 53 permits of proper positioning of the rollers 57 to prevent any binding of the rod 48 therebetween.

Means is provided for moving the side portions 47 of the shock former toward and away from each other. This means includes 125 a shift rod 58 mounted longitudinally upon the outer face of the member 42 and slidably engaged in the passage 46 between the member 42 and the bar 36, and extending beyond the end of the member 42 which is 130

connected with the bar 36. This shift rod has its opposite end mounted in a guide 59 which is also secured to the member 42. Pivoted to the shift rod 58 there are a pair 5 of diagonally extending resilient arms 60 which diverge toward the bar 36, and these arms are pivoted to the side portions 47, and thus, when the shift rod is moved in the direction of the minor ends of the side members 47 the side members will be moved 10 away from each other. When the shift rod is moved in the opposite direction the side members will be moved toward each other and to hold the shift rod with the side members separated to the fullest extent, a 15 spring 59' is engaged with the pivotal connection of the arms 60 with the shift rod and also with the inner end of the rod 48.

A stop finger 61 is carried by the shift rod 20 beyond the guide 59 and is arranged to engage the guide to limit the movement of the shift rod toward the major end of the shock former.

Means is provided for moving the shock 25 former longitudinally of the frame in both directions. This means includes a transverse shaft 62 mounted at the forward end of the frame and carrying a drum 63 which lies adjacent to the member 17 of the frame. 30 A cable 64 is looped around the drum and has its ends led oppositely therefrom. One end of the cable passes from the drum at the upper side thereof and over the member 18 of the frame and this end of the cable is 35 connected by means of a helical spring 65 with that end of the bar 36 which lies adjacent to the member 17 of the frame when the bar is at the forward limit of its movement. The opposite end of the cable is carried beneath the frame diagonally to the 40 rearward end of the member 16 of the frame where it is passed upwardly around a vertical pulley 66 carried by the rearward end of the member 16 at its inner face, beyond 45 which pulley the cable is carried forwardly and diagonally to be attached to the bar 36 at a common point with the attachment thereto of the spring 65. It will thus be seen that, with the drum rotated clockwise, 50 or with its upper portion toward the rearward end of the machine, the lower portion of the cable will be wound upon the drum and the shock former will be moved rearwardly, the upper portion of the cable un- 55 winding from the drum to permit such movement. Now, as the bar 36 which carries the shock former moves along the rails 23 and 24, the formation of these rails will shift the bar end for end with respect to 60 the machine, which will result in turning the shock former upside down, as the bar traverses the crossed portions of the rails, the rod 48 working between the rollers 57 as will be understood. The bar will then 65 travel along the rearward parallel portions

of the rails 23 and 24, and at the same time the minor end of the shock former will be elevated by the coöperation of the rollers 57 and the rod 48, the parts being so arranged that the shock former will have been brought 70 approximately to a vertical position at the time that the bar 36 reaches the rearmost portions 28 and 34 of the rails. Movement of the bar along these portions of the rails gives the shock former greater downward 75 movement with some rearward movement as will be understood. Now, if the movement of the cable be reversed, the shock former will be returned to its original position to lie open side up and with its major 80 end directed forwardly. As will be understood, when the shock former is in vertical position at the rearward limit of its movement, it lies with the free edges of its side portions directed rearwardly and with its 85 major end directed downwardly.

To rotate the drum 63, with its shaft 62 in either direction, a lateral stub shaft 67 is mounted in the member 17 of the frame and upon the inner end of this shaft there is 90 rotatably mounted a gear wheel 68 which meshes with a gear wheel 69 carried by the shaft 62, and the gear wheel 68 is provided with a clutch surface 70 upon its outer face.

Mounted upon the outer end of the shaft 95 67 there is a sprocket 71 rotatable upon the shaft and this sprocket is connected by means of an endless chain 72 with a sprocket 73 carried by the shaft 62. The sprocket 71 has an inner clutch surface 74, and the 100 clutch surfaces 74 and 70 are considerably spaced from each other to receive therebetween a sprocket 75 having oppositely directed clutch surfaces 76 and 77 for co-action with the clutch surfaces 74 and 70 105 respectively. The sprocket 75 is revolute upon the shaft 67 and is also slidable upon this shaft so that it may be moved to engage either pair of clutch surfaces. A chain 78 is engaged with the sprocket 75 and also 110 with the sprocket 22' of the bull wheel. It will thus be seen that when the clutch surfaces 74 and 76 are in engagement with each other the sprockets 71 and 73 will revolve the shaft 62 to wind the upper portion 115 of the cable upon the drum and move the shock former forwardly. When the clutch surfaces 70 and 77 are mutually engaged the gears 68 and 69 will revolve the shaft 62 and the drum in the opposite direction 120 to move the shock former rearwardly. The ratio of the gears 68 and 69 is such as to rotate the shaft 62 at such a speed that the shock former will be moved rearwardly at approximately the same rate that the entire machine is moved forwardly over the ground as the shock former traverses the rearmost portions of the rails 23 and 24 along which it passes. By this arrangement, the forward movement of the machine 130

is approximately neutralized so that the shock former is practically free from horizontal movement with respect to the ground during that portion of its movement just referred to, and during the time that it is exercising its discharging function as will be later brought out. The ratio of the sprockets 71 and 73 is such as to return the shock former to the forward end of the machine as quickly as possible consistent with proper operation.

To shift the sprocket 75 upon the shaft 67, a lever 79 is mounted in a bracket 80 secured to the frame, and is shiftable in the bracket laterally of the frame. This lever carries a yoke 80' which is engaged with the sprocket 75 for movement of the sprocket slidably upon the shaft 67. Inward movement of the lever 79 thus results in engagement of the clutch surfaces 70 and 77 while outward movement of the lever results in engagement of the clutch surfaces 74 and 76.

A cable 81 for tripping the clutch to disconnect the sprocket 75 from the sprocket 71 is provided and this cable is also utilized to bring the sprocket 75 into position to drive the gear 68. The cable 81 is connected to the lever 79, is carried through the frame transversely and is secured to a suitable foot lever 82 mounted within reach from the driver's seat of the binder A.

A rod 83 is mounted upon the member 16 of the frame to extend longitudinally thereof and to lie therebelow. This rod 83 has its forward end turned downwardly and connected by means of a link 84 with the lever 79. The rearward end of the rod 83 is turned inwardly as shown in 85 and it will be seen that downward movement of the end 85 of the rod 83 will thus result in outward movement of the lever 79, which will engage the clutch surfaces 74 and 76 for operation of the parts to move the shock former forwardly.

Means is provided for closing the shock former just prior to the beginning of its rearward movement. This means includes a spring latch secured to the member 18 of the frame and extending rearwardly and adapted to engage with a lug 87 carried by the end of the shift rod 58 which lies beyond the major end of the shock former. As shown in the drawings the spring latch is indicated at 88. The shift rod is also provided with additional lugs 89, and pivotally connected with the bar 36 there is a latch 90 which is held in position for engagement of these lugs 89 by means of a spring 91. The latch carries a trip finger 92 which extends at right angles from the shock former to project downwardly when the shock former is at the forward end of the machine in horizontal position and to project forwardly when the shock former

is at the rearward end of the machine in 65 vertical position.

Now, with the shock former at the forward end of the machine and open, it lies below the discharge table B of the binder A to receive bundles of grain therewith. 70 When filled, the foot lever 82 is operated to move the sprocket 75 from neutral position into position to drive the gear 68. This will result in rotation of the drum 63 to move the shock former rearwardly but at this time 75 the latch 88 lies in engagement with the lug 87 so that the shift rod is held stationary while the shock former moves with respect thereto. The side portions of the shock former will thus be brought together, and 80 the spring 91 will move the latch 90 into engagement with one of the lugs 89 to hold the shift rod with the shock former closed. When the stop finger 61 has been brought into engagement with the guide 59, movement of the shock former with respect to the shift rod will be arrested, if it has not already been stopped by the presence of grain within the shock former, and continued movement of the drum, tending to move 85 the shock former rearwardly will cause the lug 87 to disengage from the latch 88, this being permitted by the resilient nature of the latch, but the shock former will be held closed by the latch 90.

Now, when the shock former has reached the rearward end of the machine and is moving downwardly and rearwardly along the rearward portion of the rails, the finger 92 will be brought into contact with the 100 inwardly turned end 85 of the rod 83 which lies in position to be so engaged by the finger 92. This will result, first, in tripping of the latch 90 to release the shift rod 58, when the shock former will be thrown open 105 by the spring 59', as will be understood. The parts are so arranged that this will occur before the shock former reaches the rearward limit of its movement and since its rearward movement is also downward movement at this time the finger 92, pressing upon the end 85 of the rod 83 will move this end downwardly to throw the sprocket 75 into position to start the return movement 110 of the shock former to the forward end of 115 the machine.

The finger 92 has an additional function. It will be noted that the cable 81 extends across the frame in position to be struck by the finger 92 as the shock former is moved 120 forwardly. This occurs before the shock former has reached the forward limit of its movement and the arrangement is such that there is sufficient continued movement of the shock former to move the cable through its 125 engagement by the finger 92 sufficiently to bring the sprocket 75 and its clutch surfaces into neutral position when, of course,

the movement of the shock former will be arrested. At the same time, the lug 87 has been brought into engagement with the latch 88 and the mechanism is ready to repeat its function. It will be noted that the cable 81 contacts with the finger at a point close to the center of pivotal movement of the latch and thus there is not sufficient leverage to move the latch against the action of the spring 91 and thus interfere with the operation of the latch. However, this same function can be accomplished by a separate depending member carried by the shock former if desired.

15 The mounting of the latch 90 is shown in detail in the drawing. As previously stated, bolts 44 and 43 are passed through the bar 36 to hold the member 42 of the shock former thereto, the blocks 45 being disposed between the member 42 and the bar. At the opposite side of the bar 36 from the shock former, a bracket 93 is engaged with the bolt 44 and extends beyond the bar 36 toward the end of the shift rod 58 which carries the lug 87. This bracket has the latch 90 pivotally connected therewith and lying with its lip 90' directed toward the outer end of the shift rod and lying in position to engage the lugs 89. The finger 92 is carried by the latch and extends away from the shift rod as already described.

A bracket 94 is engaged with the bolt 43 at the opposite side of the bar 36 from the shock former and extends at right angles 35 from the bar 36 in approximately parallel relation to the finger 92. This bracket has one end 94' turned to extend over the finger 92 in spaced relation thereto and this end of the bracket has a rod 95 slidably engaged 40 therein, the rod being fixed to the finger 92 between the ends of the finger. The spring 91 is engaged with the rod 95 between the bracket 94 and the finger 92 and is arranged to hold the finger yieldably against movement toward the bracket 94 so that the finger is held with the latch 90 in position to engage the lugs 89.

Means is provided for preventing the discharge of bundles from a binder to which 50 the present invention is attached during the time that the shock former is being closed and while the shock former is traversing the rails. As has been stated, the shock former when at the forward limit of its movement 55 lies in horizontal position beneath the discharge table B of the binder A in position to receive bundles therefrom, and with its side portions separated. The bundle interrupting means comprises two brackets 96 and 97 mounted upon the side member 17 of the frame in spaced relation longitudinally of the member and at a point opposite the shock former transversely of the machine when the former is in receiving posi-

tion. These brackets 96 and 97 thus lie beneath the discharge table B as illustrated.

A horizontal shaft 98 is journaled in the upper ends of the brackets 96 and 97 and has a pair of downwardly extending lateral arms 99, one adjacent to each end. A pair 70 of arcuate fingers 100 are carried one by each of the arms 99 and extend inwardly of the machine with their extremities directed upwardly and the arrangement of these parts is such that when the shaft 98 is 75 rocked in one direction, the fingers 100 will be moved to project upwardly over the end of the discharge table to prevent the passage of bundles therefrom. From the drawings it will be seen that this occurs when the 80 shaft 98 is rocked to move the arms 99 inwardly of the machine. When the shaft is rocked in the opposite direction the fingers will be shifted to bring their upper extremities below the upper surface of the discharge 85 table.

The shaft 98 carries at its forward end a depending finger 101 which carries a laterally extending pin 110, the latter being engaged in a slot 111 formed in the upper end 90 of a rod 112, pivoted at its lower end, as shown. This rod 112 carries an outwardly extending rod 102 engaged through a guide opening 103 in the bracket 96 and provided with a stop 104 at its outer end. A spring 95 105 is engaged with the rod 102 between the finger 101 and the bracket 96, the spring being arranged to hold the finger yieldably against movement outwardly of the machine and with fingers 100 extending above the 100 discharge table in operative position.

The side portion 47 of the shock former which lies in the direction of the member 17 of the frame when the shock former is in receiving position, carries an outward extending block 106 which is provided with an outer beveled edge 107, the major end of this block being directed rearwardly so that the beveled edge 107 slants inwardly and forwardly. This block is so disposed that, as 110 the shock former is moved toward the front end of the machine, the beveled edge 107 will engage the finger 101, when further forward movement of the shock former will cause the finger 101 to move against the action of the spring 105, thus bringing the fingers 100 into inoperative position. When the shock former reaches its forward limit of movement the block 106 lies with its rearward portions of its beveled edge against the finger 101 so that the fingers 100 are held in 115 inoperative position during the filling of the shock former.

Now, as described in the foregoing when the shock former is filled, the action of the 125 mechanism is to move the side portions 47 of the shock former toward each other. When this operation takes place the block

106 will of course be moved inwardly, when the finger 101 will be free to move under the action of the spring 105 and the fingers 100 will be projected above the discharge table 5 to prevent the passage of additional bundles therefrom. By reason of the fact that the fingers 100 are curved, their points are projected not only above but over the discharge table toward the next bundle discharged and 10 thus the fingers 100 lie in position for engagement of their extremities into the bundle, thus securely holding the latter.

What is claimed is:

1. A mechanism of the class described including a frame, a shock former movably mounted in the frame and including portions movable to effect an opening or a closing of the shock former, a member connected with the movable portions of the 15 shock former for actuation of these portions to open and close the shock former when the shock former is moved with respect to the member, means for holding the said member stationary during a portion of the movement of the shock former whereby the shock former is moved with respect to the member and releasable means for holding the shock former closed.

2. A mechanism of the class described including a frame, a shock former mounted for bodily movement with respect to the frame, means for moving the shock former in opposite directions, means for actuating the moving means to move the shock former 30 in one direction, means for actuating the moving means to move the shock former in the opposite direction, said shock former including portions movable to effect an opening or a closing of the shock former, yielding 35 means for holding the shock former open, means for holding the shock former at times against the action of said yieldable means and in closed position, and means for releasing said holding means when the shock former is in a predetermined position, and 40 for reversing the movement of the shock former.

3. A mechanism of the class described including a frame, a shock former movable 50 bodily with respect to the frame in opposite directions, means for moving the shock former, said shock former including portions movable to effect an opening or a closing of the shock former, releasable means for holding 55 the shock former closed, means located in position for engagement by said holding means during movement of the shock former for release of the holding means, said releasing means being itself movable through 60 engagement by the holding means, and connections between the releasing means and the means for moving the shock former for reversing the movement of the shock

former through movement of the releasing means.

4. A mechanism of the class described including a frame, a shock former connected with the frame for bodily movement with respect thereto, said shock former including side portions movable toward and away 65 from each other, a latch member carried by the frame, a shift rod connected with the shock former, connections between the shift rod and the side portions of the shock former for movement of the side portions toward 70 and away from each other when relative movement occurs between the shift rod and the shock former, yieldable means for holding the side portions of the shock former against movement toward each other, releasable means for holding the shift rod 75 with the side portions of the shock former against the action of said yieldable means, said shift rod being positioned for engagement with the latch member to hold the 80 shift rod stationary during a portion of the movement of the shock former.

5. A mechanism of the class described including a frame, a helical track mounted longitudinally in the frame, a shock former 85 mounted for movement along the track, means for moving the shock former, said shock former being shiftable to lie at times in horizontal positions and at times in vertical positions, and means for shifting the 90 shock former from one position to the other during its movement along the track.

6. A mechanism of the class described including a frame, a track carried by the 95 frame, said track including two rails each having a substantially semi-helical bend between its ends, said rails being disposed with their semi-helical portions in crossed relation to bring the opposite ends of the rails at opposite sides of the frame, a shock former, and movable connections between the shock former and the rails for movement 100 of the shock former along the rails in either direction.

7. A mechanism of the class described including spaced rails, a carrier mounted for movement longitudinally upon the rails, said carrier being also mounted for pivotal movement with respect to the rails, a rod 105 connected with the carrier at one side of the axis of pivotal movement of the carrier, and a guide for the rod disposed above the path of movement of the carrier, said guide being adjustable transversely of said path of movement.

In testimony whereof, I affix my signature, in the presence of two witnesses.

JACOB SCHOONHOVEN.
